UNITED STATES PATENT OFFICE.

WILLIAM A. BERNARD, OF NEW HAVEN, CONNECTICUT, ASSIGNOR TO THE WILLIAM SCHOLIHORN COMPANY, OF NEW HAVEN, CONNECTICUT, A CORPORATION OF CONNECTICUT.

MEANS FOR APPLYING FASTENERS.

1,274,234.

Specification of Letters Patent. Patented July 30, 1918.

Application filed May 26, 1915. Serial No. 30,599.

To all whom it may concern:

Be it known that I, WILLIAM A. BERNARD, a citizen of the United States, residing in the city and county of New Haven and State 5 of Connecticut, have invented certain new and useful Improvements in Means for Applying Fasteners, of which the following is a full, clear, and exact description.

This invention relates to tools or devices 10 for applying or setting staples and like fasteners, and it has particular reference to hand tools designed to apply buckles and bows to shoes by means of the small staples which are generally used for this purpose.

15 The invention is, however, applicable to other uses.

The primary object which I have in view is the provision of an efficient, reliable device 20 for driving or pushing a staple through a plurality of superposed layers of material, and then clenching the ends of the staple in the material so as to form a strong, tight connection between the layers.

Another object is to provide a device 25 which can be very conveniently operated, inasmuch as means are provided for receiving and retaining the staple in the proper position preparatory to and during the piercing and clenching operation, without 30 the necessity of exercising special care in positioning the staple or operating the tool or device.

I also aim to provide a staple applying device in which the staple can be set in different positions relative to the tool, without 35 adjusting the latter. More particularly, it is aimed to provide a tool in which the staple when in position for application to the shoe or other article, can be directed either longitudinally or transversely of the tool so that 40 it can be placed in the most advantageous position on the article to which it is to be applied.

To these and other ends, the invention 45 consists in the novel features and combinations of parts to be hereinafter described and claimed.

In the accompanying drawings,

Figure 1 is an elevation of a hand tool 50 embodying my improvements, with the jaws separated;

Fig. 2 is an enlarged fragmentary view of the tool from the opposite side, certain

parts being broken away, and showing the staple in the holder; 55

Fig. 3 is a front end elevation of the tool with the handles omitted;

Fig. 4 is a considerably enlarged section of a portion of the tool, showing the completion of the staple-setting operation; 60

Fig. 5 is a view similar to Fig. 2, but with the staple holder shown in elevation and occupying another position.

Fig. 6 is an enlarged section on line 6—6 of Fig. 3; 65

Fig. 7 is a plan view of a portion of the lower jaw, showing the staple disposed transversely of the tool;

Fig. 8 is a similar view showing the staple disposed longitudinally of the tool; and 70

Fig. 9 is a fragmentary bottom view of the upper jaw, showing the die or anvil.

I have illustrated my improved staple setting means as applied to a hand tool of the parallel jaw type, such as shown, for example, in my Patent No. 665,052, dated January 1, 1901, but obviously the improvements can be embodied in tools and devices of other types. In the form shown, the tool comprises crossed lever members 10, 11 pivoted together at 12, and parallel jaws 13, 14 movable toward and away from each other. The jaw 14 is equipped with a member 15 for driving the staple through the material, and associated with said member is a staple holder 16. The driver 15 and holder 16 cooperate with a die or anvil 17 on the other jaw. 75

In the particular form illustrated, the driver 15 is square in cross section, and it is 90 suitably anchored at its lower end in an opening in the jaw 14. It serves as a guide for the holder 16, which is in the form of a sleeve embracing the driver and vertically movable with respect thereto. The opening through the sleeve-like holder conforms closely to the driver, and therefore, in the present case, it is also square in cross section, as shown in Figs. 7 and 8. 95

The holder 16 is yieldingly mounted relative to the driver by means of the following mechanism: Depending from the holder sleeve at opposite sides are cheeks or arms 18 which are guided vertically on the jaw 14 by engaging guide grooves 19 on opposite sides of the jaw. The lower ends of the arms 100

- 18 are interconnected by means of a transverse pin 20, engaged by a leaf spring 21 which may be conveniently attached to the jaw 14 at 22 by means of a screw, as shown.
- 5 The spring 21 acting against the cross pin 20 normally holds the staple holder in an elevated position relative to the driver, as shown in Fig. 2, in which position the top edge of the holder is considerably above the 10 top edge of the driver. This forms a pocket or seat for the reception of the staple 23. In this position, the staple is held in inverted position with its intermediate portion against the top surface of the driver and its 15 leg portions held upright by engaging the corners 24 of the square sleeve opening, as shown in Fig. 8. The staple fits said opening rather closely so that when the staple is dropped into the holder it will be held in a 20 position to coöperate with the anvil 17, as hereinafter described.
- In the present example, a special form of stop is used to limit the upward movement 25 of the holder (under the influence of the spring), relative to the driver. A U-shaped member 25 preferably made of sheet metal is pivoted on the pin 20 between the cheeks or arms 18 of the staple holder, and is provided with surfaces to abut the lower portion 30 of the jaw 14. In the form shown, the bent up side portions of the member 25 are perforated for the reception of the pin 20, and are provided with edge portions 26 which abut the lower surface of the jaw 14 35 when the parts are in the position shown in Fig. 2, and thereby limit the upward movement of the holder. The member 25 is provided with a thumb piece or manipulating handle 27, by which it may be swung about 40 the pivot 20 into the position shown in Fig. 5. In this last position, the edge portions 28 at the ends of the bent up side members engage the lower surface of the jaw 14 and hold the holder 16 in a depressed position.
- 45 In other words, the member 25 acts in the nature of a cam which, when swung into one position, will force the holder downward with reference to the driver and maintain it in that position. In this manner, the 50 pocket formed by the coöperation of the driver and the holder may be varied in depth as desired. Where it is found that the holder 16, when in its uppermost position (Fig. 2) is too close to the anvil for 55 the ready and convenient insertion of the staple, it may be easily lowered into the position shown in Fig. 5 by swinging down the thumb piece 27 so that the holder will then be more freely accessible.
- 60 In the operation of the device, the staple is placed in position, as shown, for example, in Fig. 2. The layers of material to be united are then interposed between the holder and the anvil, and the jaws 13, 14 65 are approached toward each other by means of the lever handles. First, the member 15 drives the staple upward through the layers of material. During this part of the operation, the staple is firmly held on top of the driver in the proper position by means 70 of the holder. As the free ends of the staple pass completely through the uppermost layer, they come into contact with the die 17 and are thereby turned over and downward into the upper layer, as shown in Fig. 75 4. During the operation of piercing the material by means of the staple, the holder is pushed down on the driver in opposition to its spring. By preference, the anvil 17 will have curved surfaces so located as to cause 80 the ends of the staple to turn down and embed themselves in the material, as shown. When the handles of the tool are released, the jaws are separated by a suitable spring 31, and the spring 21 returns the holder 16 85 to its normal position. It has been assumed that in the foregoing operation, the staple engaged the front and rear corners 24 of the holder so as to have the plane of the staple in the plane of the tool. If desired 90 to set the staple transversely of the tool, it is engaged in the other corners 29 of the holder, as shown in Fig. 7. It will be noted that one of the diagonals of the holder opening is disposed transversely of the jaw 95 14, while the other diagonal is disposed longitudinally of said jaw. The depression or clenching surface 30 of the anvil 17 is cross-shaped, so that the anvil will properly 100 clench the staple when the latter is set either longitudinally or transversely relative to the tool. Thus it will be understood that the staple can be set when in different angular relations relative to the axis of the driving member. In some cases, the staple can only 105 be set in or applied to the shoe or other article in the most advantageous position by disposing it lengthwise of the jaws, but, in other cases, the desired result can only be obtained if the staple is disposed transversely of the jaws. My improved tool takes 110 care of both of these conditions, and provides means for clenching a staple seated in a rectangular holder opening coincidentally with one or either of the diagonals of said 115 opening.
- It will be observed that the driver 15 is in the form of a prism, which, in the example shown, is of uniform cross section throughout that part which is engaged by the sliding holder 16. Furthermore, the cross section of the driver is that of a convex polygon, *i. e.*, one without reentrant angles, and the polygon is a regular polygon, *i. e.*, one in which all the sides and angles are equal. 120 The opening in the bottom of the holder is of the same cross section as the opening through the remaining portion of the holder body, so that the holder conforms to the driver throughout the length of the former. 125 130

As previously intimated, I prefer to make the driver of square cross section, as this renders the manufacture of the driver and coöperating holder a very simple matter, at 5 the same time that it provides for the seating of the staple in either of two positions in the reentrant angles of the holder which conform to and guide the holder on the projecting angles of the driving member.

10 Of course, I do not limit myself in all aspects of the invention to a construction in which the holder has only four seating corners for the staple, for obviously, the number might be varied without departing from 15 the scope of the invention. Various changes in this and other respects may be adopted within the scope of the appended claims.

What I claim is:

1. In a stapling tool, the combination of a 20 pair of jaws, a pair of lever handles for moving said jaws toward each other, a driver of rectangular cross-section fixed on one of said jaws, a holder sleeve having a rectangular opening conforming to said driver 25 and slideable thereon, said holder sleeve having cheeks straddling the jaw on which the driver is secured, a spring acting on said sleeve to normally project it beyond the end of said driver so as to form a staple-receiving 30 pocket, and an anvil on the other jaw to co-operate with said driver and said sleeve; substantially as described.

2. In a stapling tool, the combination of a 35 pair of jaws, a pair of lever handles for moving said jaws toward each other while maintaining them in parallelism, a driver fixed on one of said jaws, a sleeve embracing said driver and slideable thereon, said driver-supporting jaw having grooves in its 40 sides and said sleeve having depending cheeks guided in said grooves, a spring on said last-named jaw engaging said sleeve and normally holding it projected beyond the end of said driver to form a staple-receiving 45 pocket, and an anvil on the other jaw to co-operate with said driver and said sleeve; substantially as described.

3. In a stapling tool, the combination of a 50 pair of jaws, a pair of lever handles for closing and opening said jaws while retaining them in parallelism, a driver of square cross-section fixed on one of said jaws, a holder sleeve having a square opening engaging said driver and slideable thereon, one 55 diagonal of said sleeve opening being directed transversely of the tool, and the other diagonal being directed lengthwise thereof, said driver-supporting jaw having grooves in its sides, cheeks on said sleeve straddling 60 the jaw to which the driver is attached, and guided in the grooves of said jaw, a spring acting on said sleeve to project it beyond the end of the driver so as to form a staple-receiving pocket, and an anvil on the other 65 jaw constructed to clench the ends of a staple

traversing said pocket coincidently with either diagonal of the sleeve opening; substantially as described.

4. In a stapling tool, the combination of a pair of jaws, a pair of lever handles for 70 operating said jaws, a driver fixed on one of said jaws, a sleeve embracing said driver and slideable thereon toward and away from the other jaw, a spring normally projecting said sleeve beyond the end of the driver so 75 as to form a staple-receiving pocket, means acting on said sleeve to limit the action of said spring and hold the sleeve projected beyond the driver to a greater or less extent as desired, and an anvil on the other jaw 80 to coöperate with the driver and sleeve; substantially as described.

5. In a stapling device, the combination of a stapling member, a holder slideable thereon, a spring normally maintaining the 85 holder in a predetermined position relative to said member, and an adjustable member for limiting the action of such spring; substantially as described.

6. In a stapling device, the combination 90 of a driving member, a staple holder yielding projected beyond the end of said driving member, and a movable stop device for varying the amount of such projection; substantially as described.

7. In a stapling device, the combination of a driving member, a staple holding sleeve slideable thereon, a spring normally projecting said sleeve beyond the end of said driving member to form a staple holding pocket, 100 and a cam for limiting the action of said spring and decreasing the depth of such pocket; substantially as described.

8. In a device such as described, the combination of a driving member, a holder slideable thereon, a spring normally projecting said holder beyond the end of said driving member to form a pocket, and a stop device for said holder, said stop device movable from one position to another to decrease the 110 depth of such pocket; substantially as described.

9. In a device such as described, the combination of a supporting member, a holder, a guiding member for said holder mounted on said supporting member and on which said holder is slideable, a spring normally projecting said holder beyond the end of said guiding member to form a pocket, and a stop member abutting said supporting member to limit the depth of such pocket, said stop member adjustable to decrease the 120 depth of such pocket; substantially as described.

10. In a portable hand tool of the lever-handle type for applying staples to shoes and other articles, the combination of a pair of movable jaws, a pair of lever handles for moving said jaws toward and away from each other, a driver of substantially square 125

cross-section fixed on one of said jaws, a holder sleeve slidably mounted on the driver and having a staple-receiving pocket with one staple seat directed longitudinally of the tool and another staple seat of the same size directed at right angles to the longitudinal axis of the tool, and an anvil fixed on the other jaw and having a cross-shaped depressed portion in the face thereof in reg-

ister with the intersecting staple-receiving 10 seats of the staple pocket, whereby said anvil will effectively clench the ends of a staple traversing said pocket longitudinally of the tool or transversely thereof.

In witness whereof, I have hereunto set 15 my hand on the 25th day of May, 1915.

WILLIAM A. BERNARD.
